UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

CONTROL OF ELECTRICALLY-OPERATED SWITCHES.

1,089,820.

Specification of Letters Patent.

Patented Mar. 10, 1914.

Application filed August 12, 1910. Serial No. 576,927.

To all whom it may concern:

Be it known that I, EUGENE R. CARICHOFF, a citizen of the United States, residing at Schenectady, county of Schenectady, State of New York, have invented certain new and useful Improvements in the Control of Electrically-Operated Switches, of which the following is a specification.

My invention relates to the control of 10 electrically operated switches, and particularly to the control of a plurality of such switches or contactors intended for operation in succession. A plurality of successively operating contactors are often employed in the control of electric motors and 15 my invention is particularly adapted for use in this connection.

In one aspect my invention may be considered as an improvement on a system of control 20 for electrically operated switches covered by a patent in the name of Archibald S. Cubitt, No. 941,408, dated November 30, 1909, commonly referred to as a "two-wire notching" control system.

One of the particular improvements provided by the present invention resides in an 25 arrangement whereby one of the auxiliary switches on each of the successively operating contactors is done away with.

Another improvement resides in a particular 30 construction of notching relay mechanism.

To the above end, my invention comprises in general a system of control for a plurality 35 of contactors in which a two-wire notching relay mechanism is provided with means for effecting the alternate interruption and completion of the circuits through the actuating magnets of the relay mechanism, thereby 40 rendering unnecessary auxiliary switches on the contactors for this purpose.

My invention further comprises an arrangement of field structure in the notching relay mechanism such that but one series or 45 motor current coil is necessary, and such that the current value at which the series coil maintains the contacts of the relay mechanism open may be easily adjusted.

The drawing shows in a diagrammatic 50 manner an automatic motor starter of the

contactor type having my invention embodied therein. It is, of course, to be understood that this system is merely illustrative and that my invention may be used in a great many different arrangements of motor control apparatus.

In the drawing, the source of current is indicated at T, T', the motor to be controlled at M, and the starting resistance at R¹, R² and R³.

L is the contactor which connects the motor to the source through all of the starting resistance, and contactors 1, 2 and 3 serve to short-circuit the sections of resistance R¹, R² and R³. One terminal of the actuating coil 5 of the contactor L is connected to the negative source T' through the return wire 9, and each of the actuating coils 6, 7 and 8 of the contactors 1, 2 and 3 is connected to said return wire 9 through auxiliary contacts on the previous contactor, which contacts are closed when said contactor is closed. Each contactor except the last, therefore, in closing closes switch contacts located in the circuit of the actuating coil 75 of the succeeding contactor. The other ends of the actuating coils of the contactors 1 and 3 are connected to an actuating wire 11, while the other end of the actuating coils of the contactors L and 2 are connected to 80 an actuating wire 12, through an auxiliary switch 13 on the contactor 3 opened by said contactor in closing.

The alternate energization of the actuating wires 11 and 12 is effected by the two-wire notching relay mechanism O, which will now be described. This relay mechanism is provided with two sets of contacts o and o' located, respectively, in actuating circuits 11 and 12, said contacts being closed 85 when the actuating coils of the relay mechanism are unenergized. The movable elements of the contacts o and o' are carried by rods 15 and 16, which carry cores 17 and 18 of magnetic material, arranged for movement within the magnetic field produced by actuating coils 19 and 20, connected, respectively, through the contacts o' and the contacts o. A series coil 21 connected in the motor circuit also produces a magnetic field

which acts upon the magnet cores 17 and 18, the flux produced by the coils 19, 20 and 21 being given a path of low reluctance by means of the iron magnet frames 23 and 24, 5 arranged as shown. The path of the flux produced by the series coil 21 is further improved by the core 25 of magnetic material which is made adjustable in the frame 24 by being screwed therein, as clearly 10 shown. By screwing the core 25 up and down the air gap between the end thereof and the frame 23 can be varied and the influence of the series coil 21 upon the cores 17 and 18 can thereby be regulated.

15 Above the structure of the relay mechanism just described is located a switch mechanism which comprises a double bell-crank lever pivoted at 27, having arms 28 and 29 adapted to be engaged by the rods 15 and 16 20 in their upward movement. The arm 30 of the bell-crank lever serves as a movable switch member and engages with fixed contact clips 31 and 32 connected respectively through wires 33 and 34 to the coils 19 and 20. 25 The contact member 30 is connected through a wire 35 and a master switch K to the positive side of the source. The wire 36 also is connected to the positive side of the source through switch K, and serves as a 30 maintaining wire by being connected through the resistances r and r' with the actuating wires 11 and 12. In the operation of the notching relay mechanism the upward movement of the rods 15 and 16 causes 35 the double bell-crank lever to be thrown first to one side and then the other, thereby alternately connecting the contact clips 31 and 32 to the positive side of the source through switch K. This lever is constructed 40 to make contact on 32 before breaking on 31, and vice versa.

If desired, the notching relay mechanism may be given a "time limit" and for this purpose I have shown dash pots having 45 their cylinders 38 and 39 connected to the rods 15 and 16, respectively, the pistons 40 and 41 being connected by rods 43 and 44 to the fixed abutment 45. The connection between the rods 43 and 44 and the abutment 50 45 should be a lost-motion one, such as that indicated in the drawing, in which said rods are provided with collars which engage the fixed abutment 45 on its upper and lower sides, the rods being arranged to slide freely 55 through holes in said abutment. The cylinders of the dash-pots are provided with valves 47 and 48 which allow air to escape from above the pistons, as will be apparent from the drawing. In the arrangement 60 shown, therefore, the dash-pots do not interfere with the initial upward movement of the rods 15 and 16 carrying the movable members of the contacts σ and σ' , but do retard the further upward movement of said

rods and thereby delay the operation of the 65 switch member 30. The contacts σ and σ' are not delayed, therefore, in their opening movement by the dash-pots.

The mode of operation of the system shown in the diagram is as follows: All the 70 contactors being open and the motor being at rest, when the switch K is closed current will flow from the positive side of the source through said switch, wire 35, switch member 30, contact clip 31, wire 33, coil 19, contacts 75 σ' , actuating wire 12 and through actuating coil 5 of the contactor L to the negative side of the source. The contactor L will, therefore, close and the motor circuit will be completed through all of the resistances R^1 , R^2 80 and R^3 . When the coil 19 is energized and prior to or coincident with the closing of the contactor L, the core 17 will move upwardly, thereby immediately opening the contacts σ located in the circuit with the actuating wire 85 11. The last part of the upward movement of the rod 15 attached to the core 17 is retarded by the dash-pot coöperating with it as hereinbefore explained, but eventually the rod 15 engages with the arm 28 of the double 90 bell-crank lever and throws the contact member 30 from engagement with the contact clip 31 into engagement with the contact clip 32. This will immediately result in interrupting the connection of the wire 33 with 95 the positive side of the source and in the de-energization of the coil 19 and the actuating wire 12. The actuating coil 5 of the contactor L, however, is provided with sufficient 100 current to maintain said contactor closed, through the maintaining circuit which may be traced from the switch K, through the wire 36 and the resistance r . Upon the de-energization of the coil 19 its coöperating core 17 will be free to drop unless it is main- 105 tained in its upper position by the magnetizing effect of the series coil 21 connected in the motor circuit. This coil 21 is so de- 110 signed and the air gap between the movable core 25 and the magnet frame 23 is so ad- justed that the cores 17 and 18 will be mag- netically held in their upper position as long as the current in the motor circuit ex- 115 ceeds a certain value. If, therefore, after completion of the motor circuit by closing of 115 the contactor L the current in said circuit exceeds the value just mentioned, the core 17 will be held in its raised position and the cir- 120 cuit from the positive side of the source through the switch K, wire 35, contact mem- ber 30, contact clip 32, wire 34 and coil 20 will be interrupted at the contacts σ , and the actuating wire 11 will not be energized, al- 125 though the negative side of the actuating coil 6 of contactor 1 has been connected to the negative side of the source through aux- illiary contacts on the contactor L. The con- tactor 1 will, therefore, not be closed until

the speeding up of the motor, with the consequent increase in counter-electromotive force, has cut down the current in the motor circuit below the value at which the coil 21 holds up the core 17. When this occurs, the core 17 drops and the contacts σ are immediately closed, thereby completing the actuating circuit just traced for the actuating coil 6 of the contactor 1 and causing said contactor to close, which results in short-circuiting the section of resistance R^1 . Prior to or coincident with the closing of the contactor 1, the core 18 is attracted in an upward direction by the coil 20 and the contacts σ' are opened, exactly as in the case of the other contacts σ of the relay as just described. The actuating circuit 12 will not be energized immediately, therefore, when the contact member 30 is thrown out of engagement with the contact clip 32 and back into engagement with the contact clip 31 by the final upward movement of the core 18 and the rod 16. The contactor 1 will be maintained in its closed position by current received through the maintaining wire 36 and resistance r' , similarly to the manner in which the contactor L is maintained. If the closing of the contactor 1 results in increasing the motor current to or above the value at which the coil 21 of the relay is effective, the core 18 will be held in its upper position, and the contacts σ' will not close until the speeding up of the motor has reduced the motor current. When this happens the contacts σ' close and the actuating wire 12 is re-energized as before, thereby causing closing of the contactor 2 owing to the energization of actuating coil 7 which is connected to said wire. In the further operation of the system the actuating wire 11 is again energized and the contactor 3 is finally closed. Closing of the contactor 3 opens the auxiliary switch 13 and prevents further operation of the notching relay mechanism. It will be seen from the foregoing that the contactors L, 1, 2 and 3 will close in succession automatically under the control of the notching relay mechanism and subject to the "current limit" provided by the coil 21 and to the "time limit" introduced by the dash-pots forming part of the relay mechanism.

It is, of course, to be understood that my invention may be embodied in a great variety of control systems, and that the notching relay mechanism which I have shown may be modified in many ways without departing from the spirit of my invention as defined by the following claims.

What I claim as new and desire to secure by Letters Patent of the United States, is,—

1. In combination, a plurality of contactors, two actuating circuits leading to alternate contactors, normally open switch contacts co-operating with each contactor except the last and closed by said contactors in closing located in the actuating circuit of the succeeding contactor, means for maintaining said contactors closed independently of said actuating circuits, and a relay mechanism for energizing said actu-

65
6. In combination, a plurality of contactors, two actuating circuits leading to alternate contactors, normally open switch contacts co-operating with each contactor except the last and closed by said contactors in closing located in the actuating circuit of the succeeding contactor, and a relay mechanism for energizing said actuating circuits alternately comprising two sets of switch contacts one located in each of said actuating circuits, a magnet for opening each of said switch contacts each magnet having its coil connected in series with the other switch contacts, and a switch mechanism actuated by said magnets for completing the circuit 75 through the coils of said magnets alternately.

2. In combination, a plurality of contactors, two actuating circuits leading to alternate contactors, normally open switch contacts co-operating with each contactor except the last and closed by said contactors in closing located in the actuating circuit of the succeeding contactor, and a relay mechanism for energizing said actuating circuits alternately comprising two sets of switch contacts one located in each of said actuating circuits, a magnet for opening each of said switch contacts each magnet having its coil connected in series with the other switch contacts, and a switch mechanism actuated by said magnets for completing the circuit 80 through the coils of said magnets alternately.

3. In combination with a power circuit, 95 a plurality of contactors intended for operation in succession to effect certain connections in said power circuit, two actuating circuits leading to alternate contactors, a normally open switch co-operating with each 100 contactor except the last and closed by said contactors in closing located in the actuating circuit of the succeeding contactor, and a relay mechanism for energizing said actuating circuits alternately comprising 105 two sets of switch contacts one located in each of said actuating circuits, a magnet for opening each of said switch contacts each magnet having its coil connected in series with the other switch contacts, a magnet energized from the power circuit for controlling the closing of said switch contacts, and a switch mechanism actuated by said first mentioned magnets for closing connections 110 in the circuits through the coils of said magnets alternately.

4. In combination with a power circuit, a plurality of contactors intended for operation in succession to effect certain connections in said power circuit, two actuating 120 circuits leading to alternate contactors, a normally open switch co-operating with each contactor except the last and closed by said contactors in closing located in the actuating circuit of the succeeding contactor, means 125 for maintaining said contactors closed independently of said actuating circuits, and a relay mechanism for energizing said actu-

- ating circuits alternately comprising two sets of normally closed switch contacts one located in each of said actuating circuits, a magnet for opening each of said switch contacts each magnet having its coil connected in series with the other switch contacts, a third magnet energized from the power circuit for controlling the closing of said switch contacts, and a switch mechanism actuated by each of said first mentioned magnets for opening the circuit through the coil of the energized magnet and closing a connection through the coil of the other magnet.
- 15 5. A relay mechanism comprising two sets of normally closed switch contacts, a magnet for opening each of said switch contacts, each magnet having its coil connected in series with the other switch contacts, and a switch mechanism operated by each magnet for opening a connection in the circuit through that magnet and for closing a connection in the circuit through the other magnet, whereby circuits through said magnets will be completed alternately.
- 20 6. A relay mechanism comprising two sets of normally closed switch contacts, two actuating coils each connected in series with one of the sets of switch contacts, a movable core 30 of magnetic material coöperating with each actuating coil and operatively connected to the switch contacts in the circuit of the other actuating coil whereby energization of one actuating coil effects opening of the contacts in the circuit of the other actuating coil, a switch mechanism having two positions in which it closes contacts in circuit with one or the other of said actuating coils, and an operating connection between said cores and said switch mechanism whereby each core in its movement in response to the energization of its actuating coil throws said switch mechanism to the position in which it interrupts the circuit through said actuating coil and completes a circuit through the other actuating coil.
- 25 7. A relay mechanism comprising two sets of normally closed switch contacts, a magnet for opening each of said switch contacts, each coil having its magnet connected in series with the other switch contacts, a third magnet for controlling the closing of said switch contacts, and a switch mechanism operated by each of the first mentioned magnets for opening a connection in the circuit through that magnet and for closing a connection through the circuit of the other magnet whereby circuits through said magnets will be completed alternately.
- 30 8. A relay mechanism comprising two sets of normally closed switch contacts, two actuating coils each connected in series with one of the sets of switch contacts, a movable core of magnetic material coöperating with each actuating coil and operatively connected to the switch contacts in the circuit of the other actuating coil, a third magnet coöperating with said movable cores and arranged to control the closing of said switch contacts, a switch mechanism having two positions in which respectively it closes contacts in circuit with one or the other of said actuating coils, and an operating connection between said cores and said switch mechanism whereby each core in its movement in response to the energization of its actuating coil throws said switch mechanism to the position in which it interrupts the circuit through said actuating coil and completes a circuit through the other actuating coil.
- 35 9. In a relay mechanism, two actuating magnet coils, movable cores of magnetic material coöperating therewith, normally closed switch contacts opened by said cores in their initial movement in response to the energization of said actuating coils, a switch mechanism actuated by said movable cores in their final movement and having two positions in which respectively it completes a connection in circuit with one or the other of said actuating coils, and retarding devices for retarding the final movement of said cores in response to the energization of said actuating coils.
- 40 10. In a relay mechanism, a plurality of actuating magnet coils, movable cores of magnetic material coöperating therewith, switches operated by said cores in their movement, another magnet arranged to affect said cores comprising a magnetic winding and magnetic circuits including a common air gap and means for varying said air gap.
- 45 11. In a relay mechanism, a pair of actuating magnet coils, movable cores of magnetic material coöperating therewith, switches operated by said cores in their movement, a third magnet between said magnets arranged to affect said cores comprising a magnetic winding and two magnetic circuits having a common branch including an air gap, and means for varying said gap.
- 50 12. In a relay mechanism, a plurality of actuating magnet coils, movable cores of magnetic material coöperating therewith, switches operated by said cores in their movement, another magnet arranged to affect said cores comprising a magnetic winding and magnetic circuits having a common magnetic core in said winding and including an air gap and means for varying said air gap.
- 55 13. In a relay mechanism, two actuating magnet coils, a movable core of magnetic

material coöperating with each of said coils, a third magnet coil located between the other two coils and coöperating with both of said cores, two substantially parallel bars of magnetic material between which the three coils are arranged, a third core of magnetic material adjustable within said third mentioned coil for regulating the reluctance of

the path through said coil, and switches actuated by said cores in their movement.

In witness whereof, I have hereunto set my hand this 11th day of August 1910.

EUGENE R. CARICHOFF.
